ATTORNEYS,

UNITED STATES PATENT OFFICE.

ADOLF HOMMEL, OF ZURICH, SWITZERLAND.

RESERVOIR-PEN.

SPECIFICATION forming part of Letters Patent No. 394,183, dated December 11, 1888.

Application filed July 16, 1888. Serial No. 280,076. (No model.)

To all whom it may concern:

Be it known that I, ADOLF HOMMEL, doctor of medicine, a citizen of Switzerland, residing at Zurich, Switzerland, have invented 5 new and useful Improvements in Reservoir Pens, of which the following is a specification.

The object of my invention is a fountain-pen which is so constructed that the pen-holder is the reservoir holding the ink, which 10 latter is forced into the pen-nib and withdrawn from the same by a piston operating within the said pen-holder.

In the accompanying drawing is shown a 15 longitudinal sectional view of a pen-holder embodying my invention.

According to this invention I construct a fountain pen-holder as follows: Within a cylindrical lower part, C, of the pen-holder is contained a piston, K, having a stem, K', of 20 elliptic section, and having a screw-thread formed on it. This stem passes upward first through an elliptic hole in a disk, S, fixed in a socket, B, which is adjusted on the upper 25 end of the said cylindrical lower part, C, of the stem, whereby the piston and its stem are prevented from rotating; and, secondly, the stem passes through a screwed nut, M, that is held in the socket B, so that it can be rotated, but cannot shift up or down. To this nut is 30 fixed a tubular cap, A, forming the upper part 35 of the pen-holder, and in which is contained the upper part of the piston-stem K'. Thus on rotating the cap A, and with it the screw-nut B, in one direction or the other, the piston K and its stem K' are moved up or down in the cylindrical part C of the holder. The lower end of this latter is closed by a cap, H, formed with a socket for the reception of an ordinary steel or other pen, F, and it has also 40 a small tube, R, projecting from it on the under side of the pen, so that its open outer end is situated against the point of the latter. Thus assuming the piston to have been moved

to the lower end of the cylindrical part of the holder, then on holding the pen-holder so that 45 the said small tube is immersed in ink, and turning the cap at the upper end so that the piston is drawn upward thereby, the ink will be drawn into the cylindrical part of the holder, so as to charge this with a supply of 50 ink.

On using the pen-holder the cap is gradually turned in the contrary direction, so as to force the piston downward, thus causing the 55 ink to flow from the tube into the pen.

The stem K' of the piston K can also be formed hollow, with an internal screw-thread, and the rotatable nut B be situated inside it and connected by a stem to the upper end of the cap A.

Having thus described my invention and the manner of employing the same, what I claim as my invention, and wish to have secured to me by Letters Patent of the United States of America, is—

1. A fountain pen-holder which is filled with ink and ink supplied to the pen by simply turning a stem, and thus raising or lowering a piston by means of a threaded piston-rod and a nut attached to the other half of 70 the pen-holder to that in which the piston works.

2. In a fountain pen-holder, the piston K, the stem K', and disk S, fixed in the socket B, in combination with the screwed nut M 75 and tubular cap A, all substantially in the manner and for the purpose described and shown.

In testimony whereof I have signed my name to this specification in the presence of two sub- 80 scribing witnesses.

ADOLF HOMMEL.
